Wm. L. & F. W. Wrigley, Baltimore, Md.

Seller's Patent

The device or device referred to in this Seller's Patent and making part of the same containing a description in the words of the said Frederick Wrigley himself of his improvement in pump.

It is known that, Frederick Wrigley of Baltimore in the County of Baltimore and State of Maryland have made a new and useful improvement in things to prevent the introduction of hard substances through the top, handle, pump and pump which would impede the operation of the pump; the following being a full and exact description of the construction and operation of the same as invented or improved by me.

Article 1° B. C. & D. (See the annexed drawings) represent the piston plate made of cast iron or brass in one solid piece and secured fast with two screw bolts having a round bar in front of the flat plate on the opposite sides of the piston being secured fast in or to the

B. 2. represents a side view of the piston plate with the bar in which the pin of the handle works and the lower end which receives the cross bar of the handle attached to receive the plate which is fastened to the cap of the pump.

B. 3. represents the inside of the piston plate which may have its position in the pump reversed in case the water should be shat down in order to increase the leverage of the handle.

Article 2°, C. C. & D. The handle is brass, ... A hole which receives the pin is nearly round the hole to receive the pin being a half inch from its center to the end of the bar of handle. D. bent in the form of a hook to receive the piston or piston with a plate secured on the top; the end of a thin plate retaining a small hole in the end of the hook. C. 2. the screw, C. 3. the plate

Article 3° D. C. 1. The pump made of wood or iron with this improvement there are apertures through which the water escape it made crooked instead of straight as represented in the drawing D. 3. which prevents any injurious substance getting into the pump thro' the pipe.

Article 4. To represent a completion of the cap of Article 3. The above hole with a common barplate for securing the interum plate and a present the pump splitting the bar it is understood that the handle may be removed when necessary. Article 5. On the upper end of the pump a plate made of iron and square at the top. In the common piston this plate is firmly made with a lock. Article 6. To the lower bolt a fastening for the cap Article 7. A lot of plate bent at one end downwards at right angles when made down to the top of the interum plate together with a square hole at the other end to receive the upper end of interum plate made in the form of a lock. 8. The small plate that which the screen passes 9. A perspective view of plate 8. For a further illustration of my invention I refer to the annexed drawings and the model deposited in the Patent Office. What I claim as my invention and improvement to which I have a Letters Patent, is all that part of the pump described from Article 1 to Article 8 inclusive; except the part of the handle projecting from the pump & the cap. In testimony whereof I hereunto subscribe my name this 28th day of January 1833
